DRAWING TOY

Denys Fisher, Collingham, England, assignor to Denys Fisher Group Limited, Boston Spa, Yorkshire, England, a corporation of Great Britain

Filed Sept. 25, 1967, Ser. No. 8,732

Claims priority, application Great Britain Mar. 31, 1967

Term of patent 14 years

Int. Cl. D19—07

U.S. Cl. D25—1

FIG.1

The side shown in FIGURES 2 and 3 is the front side of the drawing toy and the rear side, not shown, is identical to the views shown in FIGURES 2 and 3.

The bottom is generally planar and not ornamented.

I claim:

The ornamental design for a drawing toy, as shown and described.
